SHANK AND BIT PUNCH

Filed June 13, 1929

UNITED STATES PATENT OFFICE

JESSE DITSON, OF LITTLETON, COLORADO, ASSIGNOR TO INGERSOLL-RAND COMPANY,
OF JERSEY CITY, NEW JERSEY, A CORPORATION OF NEW JERSEY

SHANK AND BIT PUNCH

Application filed June 13, 1929. Serial No. 370,640.

This invention relates to bore forming machines, such as shank and bit punches, but more particularly to a throttle valve control for machines of this type.

One object of the invention is to facilitate the starting and stopping of the shank and bit punch by enabling the percussive element of the machine to be set in operation without necessitating the manipulation of means other than the work intended to be re-bored.

Other objects will be in part obvious and in part pointed out hereinafter.

In the drawings illustrating the invention and in which similar reference characters refer to similar parts,

Figure 1 is a longitudinal sectional elevation of a shank and bit punch constructed in accordance with the practice of the invention, and showing the throttle valve in the closed position, and

Figure 2 is a longitudinal elevation partly in section of the punch showing the manner in which the throttle valve is held in the open position.

Referring more particularly to the drawings, A designates a shank and bit punch comprising a cylinder B in which is formed a piston chamber C to accommodate a reciprocatory hammer piston D. A front head E forms a closure for the front end of the cylinder B and a back head F serves in a similar capacity at the rearward end of the cylinder.

In the drawings the hammer piston D is illustrated as being of the differential type having a head G and a stem H, the rearward end J of which is a constant pressure surface while the forward surface K and the rearward surface L of the head G are only intermittently exposed to pressure fluid.

The hammer piston D is provided with a central bore O to slidably receive an anvil block P which extends throughout the length of the machine and is guided at its forward end by the front head E. In the projecting or extreme forward end Q of the anvil block P is a socket R for the reception of a punch pin S adapted to re-form the bore of hollow articles, as for instance, a passage T in a drill steel U.

The anvil block P may be of a well known type having a collar V against which the surface K of the piston D is adapted to strike for driving the punch pin S into the drill steel U. At a point on the anvil block adjacent the rearward end of the piston chamber C is a removable head W against which an end surface X of a recess Y in the piston D is adapted to strike for driving the punch pin S rearwardly as for instance for withdrawing the punch pin from the drill steel.

The rearward end Z of the anvil block P is of somewhat smaller diameter than the main body portion of the anvil block and carries at its extreme rearward end a head b which acts as an abutment for a split sleeve c serving as a seat for a spring d disposed about the end Z. The rearward movement of the split sleeve c is limited by a shoulder e in a cap f seated on the rearward end of the back head F. Abutting the rearward end of the back head F is a split sleeve g through which the end Z of the anvil block is adapted to slide and said sleeve acts as a seat for the opposite end of the spring d.

The distribution of pressure fluid to the piston chamber is in this instance effected by the stem H of the piston D and pressure fluid admitted into the rearward end of the piston chamber flows through an inlet passage h leading to a point near the forward end of the piston chamber C. Such pressure fluid is conveyed to the rearward end of the piston chamber through a supply passage j leading from a throttle valve chamber k in the cylinder B.

From the supply passage j branches a passage o to supply pressure fluid to the actuating surface L of the head G of the piston. Such pressure fluid flows around a neck p of the piston stem H which overruns the passage o in the rearward limiting position of the piston D. A free exhaust port B' in the cylinder is controlled by the head G of the piston.

The throttle valve chamber k may communicate with a source of pressure fluid supply through a pipe q and the flow of pressure fluid from the throttle valve chamber k is controlled by a throttle valve r of the poppet

type normally held closed by a spring *s* seated with one end on the throttle valve *r* and with its other end against a plug *t* threaded into the end of the throttle valve chamber *k* to form a closure therefor.

5 In order that the throttle valve *r* may be conveniently manipulated by means of the work, such as the drill steel *U*, a lever *u* is pivoted forwardly of the cylinder *B*, as for instance, on a guide *v* secured to the front end the cylinder and having a groove *w* to accommodate the drill steel *U* in a position coaxially with the punch pin *S*. The lever *u* is preferably of T-shape, the bar *x* of which is provided at one end with an aperture *y* to receive a pivot pin *z* which may be seated with its ends 2 in the guide *v*. The opposite end 2 of the bar *x* is adapted to oscillate in a slot 3 in the guide and the ends of said slot 3 may serve to limit the oscillatory movement of the lever *u*.

10 In the construction shown, the bar *x* of the lever *u* lies across the end of a stem 4 of the throttle valve *r*, and a spring 5 disposed about the free end of the stem 4 bears with one end against the bar *x* and with its other end is seated in a cavity 6 in the cylinder *B*.

15 The function of the spring 5 is to normally maintain the lever *u* in its retracted position so that the throttle valve *r* may be held closed by its spring *s*.

20 In the retracted position of the lever *u* a bearing portion 7 thereof will be held at an elevation somewhat higher than the bottom 35 of the groove *w* and will thus lie across the path of the punch pin *S*.

25 In the following description of the operation of the device the course of the pressure fluid from the valve chamber *k* to the piston chamber *C* and the distribution thereof will be omitted since the manner in which this distribution is effected is well known as are also the elements whereby it is distributed. The description of the operation will therefore be confined to the pressure fluid controlling means, such as the throttle valve and the means whereby the throttle valve is actuated.

30 Whenever it is desired to set the machine in operation, the work, such as the drill steel *U*, may be laid on the bearing portion 7 of the lever *u* and the work will oscillate the lever *u* about its pivot *z*. This movement of the lever will cause the bar *x* to open the throttle valve *r* and permit pressure fluid to flow from the throttle valve chamber *k* into the supply chamber. From thence it will be distributed to the various portions of the piston chamber to set the piston *D* in operation.

35 Owing to the action of the spring *d* the anvil block *P* will remain in a neutral position, that is, it will occupy a position in which both the collars *V* and *W* will be out of the range of travel of the hammer piston *D*.

40 After the lever *u* has been depressed to a

point where the drill steel *U* will lie in the groove *w*, the drill steel may be pressed against the punch pin *S* and by continuing such pressure in a rearward direction, the collar *V* of the anvil block will be moved into the front end of the piston chamber *C* to receive the blows of the hammer piston *D*. In this way the punch pin *S* will be rapidly driven into the drill steel.

45 After the punch pin has penetrated the passage *T* in the drill steel to the desired depth, the drill steel *U* may be drawn away from the punch pin and, owing to the tendency of the heated metal to adhere to the punch pin *S*, the anvil block *P* will also be moved forwardly with the drill steel. This movement of the anvil block will carry the collar *V* out of the range of the hammer piston and will move the collar *W* into the rearward end of the piston chamber to enable the surface *X* to strike thereagainst. In this way the punch pin *S* will be speedily withdrawn from the drill steel *U*. After the punch pin *S* has been removed from the drill steel, the drill steel may be raised from the bearing portion 7 of the lever *u* and the spring 5 will then oscillate the lever *u* to its retracted position and this movement of the lever *u* will enable the spring *s* to close the throttle valve *r*, thus completing the cycle 50 of operations.

55 In practice the present invention has been found to be very satisfactory since it eliminates the necessity of manipulating means other than the work for starting and stopping the punch. This is extremely desirable in devices of this character wherein the slightest delay in manipulating the pressure fluid controlling means, such as the throttle valve may result in a strong engagement between the heated metal of the drill steel and the comparatively cold punch pin *S* and, in consequence, a considerable amount of time is frequently spent in efforts to remove the punch pin from the work.

60 I claim:

1. In a shank and bit punch, the combination of a cylinder having a piston chamber and a hammer piston in the piston chamber, a punch pin adapted to be actuated by the piston, a valve chamber in the cylinder, a passage for conveying pressure fluid from the valve chamber to the piston chamber, a throttle valve in the valve chamber to control the passage, a guide to support the work coaxially with the punch pin, and means pivoted on the guide adapted to be actuated by the work for actuating the throttle valve.

65 2. In a shank and bit punch, the combination of a cylinder having a piston chamber and a hammer piston in the piston chamber, a punch pin adapted to be actuated by the piston, a valve chamber in the cylinder, a passage for conveying pressure fluid from the valve chamber to the piston chamber, a

throttle valve in the valve chamber to control the passage, a guide to support the work coaxially with the punch pin, a lever pivoted on the guide and adapted to be oscillated in one direction by the work for opening the throttle valve, and a spring for actuating the lever in the opposite direction.

3. In a shank and bit punch, the combination of a cylinder having a piston chamber and a hammer piston in the piston chamber, a punch pin adapted to be actuated by the piston, a valve chamber in the cylinder, a passage leading from the valve chamber to the piston chamber, a throttle valve in the valve chamber to control the passage, a guide secured to the cylinder and having a groove to maintain the work coaxially with the punch pin, a lever pivoted at one end to the guide and acting against the throttle valve, a bearing portion on the lever against which pressure is applied by the work for opening the throttle valve, and a spring acting against the lever to normally maintain the bearing portion at a higher elevation than the groove.

25 In testimony whereof I have signed this specification.

JESSE DITSON.
